ICE TRAY GRID

Clifford R. Carney, Miami, Fla., assignor to Cellon Corporation, Miami, Fla., a corporation of Florida

Application October 10, 1946, Serial No. 702,497

1 Claim. (Cl. 62—108.5)

1 The present invention relates to ice tray grids and more particularly to ice tray grids which are removable from an ice tray, and which may be readily operated to secure the release of the ice cubes therefrom.

The problem of freeing ice cubes from a tray in which they are frozen in a conventional type of mechanical refrigerator is one which has been long present in this art. The attempts to solve the problem have generally taken one of two directions. First, the provision of a grid formed of a resilient material, such for example as rubber or the like, which may be distorted to break the bond between the grid and the cubes, and thus to free the cubes from the grid. Second, the provision of a grid having rigid partitioning members, certain of which are movable relative to the others for the purpose of breaking the adhesion between the ice cubes and the rigid elements of the grid construction.

In both general forms of the prior grids the grid mechanism and the ice when frozen presents a rigid mass in which the grid, whether resiliently flexible or whether mechanically united for movement of one rigid section relative to the other is held immobile in the ice block.

As distinguished from previously known types of grids, the grid of the present invention is composed of a plurality of separate elements loosely joined together in such a manner that a force imparted to the pan by twisting or distorting the pan or by a sharp blow thereon is transmitted through the ice to the transverse members of the grid frozen in the ice in the pan and effects movement of said transverse members independently of any movement of the longitudinal member of the grid. This movement of the transverse members of the grid provides for the release of the ice cubes from the grid immediately after the frozen grid and ice block has been released from the pan.

It is an object of the present invention to provide an ice tray grid having a plurality of transverse grid members loosely connected with arcuate slots in a longitudinal member which permits sliding movement of the transverse grid members relative to the longitudinal member to effect a shearing and ice breaking movement of the grid members to free the grid from the frozen ice block.

A further object of the present invention is to provide an ice tray grid formed of a plurality of separate rigid elements so united in the assembled structure that each element is relatively

movable with respect to the other elements of the grid and in which relative movement of the parts may be initiated by a force applied directly to the pan in which the grid and ice block is frozen, the resultant separate movement of the transverse members relative to the longitudinal member effecting separation of ice cubes from the grid.

A further object of the present invention is to provide an ice tray grid formed of a plurality of relatively movable rigid members which may be readily assembled from its separate component parts, thus achieving substantial economies in the mass production manufacture thereof.

15 It is a further object of the present invention to provide an ice tray grid formed of a plurality of movable rigid elements so constructed and assembled that when placed in an ice tray, each element of the grid structure will occupy its pre-determined position for an efficient mechanical movement of the parts for breaking the grid from the ice block frozen therein.

Other objects of this invention will appear in the following description and appended claim, reference being had to the accompanying drawings forming a part of this specification wherein like reference characters designate corresponding parts in the several views.

In the drawings:

30 Fig. 1 is a top plan view showing an ice tray in which is placed a grid embodying the present invention.

35 Fig. 2 is a longitudinal section taken substantially on the line 2—2 in the direction of the arrows Fig. 1.

Fig. 3 is a view similar to Fig. 2 but showing the pan in an inverted position and parts of the grid moved to their positions for freeing and removing ice cubes therefrom.

40 Fig. 4 is a fragmentary section taken substantially on the line 4—4 in the direction of the arrows, Fig. 2.

Before explaining in detail the present invention it is to be understood that the invention is not limited in the application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The grid construction here shown comprises a plurality of separate transverse members 10, an-

gularly disposed in the grid structure and spaced from each other longitudinally by a longitudinally extending spacer member formed of a separate upper member 11 and a separate lower member 12 secured at their ends preferably by rivets 13 and 14. Any other desired means for securing the ends of the members 11 and 12 forming the longitudinal separator member may be employed in place of the rivets 13 and 14.

A plurality of arcuate slots 15 are provided in the members 11 and 12. The arcuate slots 15 are designed as cam members to guide the transverse members 10 to effect a vertical and pivotal movement thereof relative to the other parts of the grid. The transverse members 10 are each provided with a cam follower portion 16 which extends into the arcuate slot 15 and acts to position the transverse member 10 in the slot 15. The dimensions of each of the transverse members 10 is such as to fit within one of the slots 15 and to be movable relative thereto. The slots 15 and the cam followers 16 thus arranged, provide guides which hold the members 10 in the desired angular positions relative to the longitudinal member. The slots 15 are of such lengths as to accommodate the assembly of the members 10 with sufficient play to permit free sliding movement of the members 10 relative to each other and relative to the longitudinal partition. Any substantial movement of the members 10 relative to each other or relative to the longitudinal member in either a horizontal or a longitudinal plane is prevented by this construction.

Each of the transverse members 10 is provided with cut-away slot portions 19 and 20 which extend over the upper member 11 and the lower member 12 and permit relative movement between said transverse members 10 and the longitudinal partition member.

When the transverse grid members 10 are in the position shown in Fig. 2, it will be seen that the angular arrangement of the members provides a plurality of spaces indicated generally by the arrows and numerals 21, 22 and 23. In each of these spaces the side walls extend angularly toward each other in the general shape of a truncated wedge whose base lies adjacent the top portion of the grid and whose truncated apex is directed toward the pan 24. This arrangement also provides similarly shaped spaces indicated by the arrows and numerals 25 and 26 whose bases are adjacent the pan 24 and whose truncated apices are directed toward the top of the grid. By this construction, a wedging action is exerted by the ice cubes frozen in the grid when a force causing distortion of the pan is applied thereto.

As shown in Fig. 3, a sharp blow, indicated by the directional arrow 31, causes a distortion of a portion of the bottom of the pan. The distortion of the pan is transferred to the rigid ice mass and this ice mass is freed from the pan. In place of a sharp blow, a similar effect is produced by twisting the frozen pan. The force causing distortion of the pan is transferred to the wedge-shaped ice cubes occupying the space 22 and causes the cubes to exert a wedging effect on the adjacent transverse members 10. The force also is transferred through the bottom portions of the pan 24 and to the bottom portions of the ice blocks occupying the spaces 25 and 26. These blocks exert an upwardly directed force on the adjacent transverse members 10 which are then free to move in the arcuate cam slots 15 relative to the pan and to exert an ice-freeing force on

the blocks occupying the space between the blocks in the space 22 and the blocks occupying the spaces 25 and 26. It will be seen that the wedge-shaped spaces 25 and 26 forming wedge-shaped blocks therein act in effect to multiply the forces causing the freeing of the grid and blocks. This movement is permitted since the first force as here shown, has caused the central block to be freed from the space 22. This block is essentially a key which when freed from the grid provides adequate space for the required sliding movement of all of the transverse members 10 so as to assure the freeing of all of the blocks held in the grid between the transverse members 10. The exerting of the force by the wedge-shaped blocks in the spaces 25 and 26 also acts to separate the grid from the pan.

While Fig. 3 shows the pan in an inverted position in order to clarify the present disclosure, it is to be understood that it is not necessary to invert the pan for the purpose of freeing the ice blocks since the above described movements will be noted in response to distorting forces applied to the pan even though the pan is in its normal upright position.

The assembly of the separate elements to form the grid structure herein shown is economically achieved on a mass production basis by first stamping each of the parts separately and, if desired, treating the parts to provide the surface protection thereof. The members 10, 11 and 12 may be stamped separately from aluminum sheet stock and thereafter anodized and sealed to render the surfaces impervious to moisture. The assembly may then be completed of the parts thus treated. Usually, however, it is more economical to anodize and seal the parts after they are assembled. The present grid construction is ideal for such treatment as the loose assembly of the parts here provided will permit the complete anodizing and sealing of the assembled grid.

In assembling the grid, the lower longitudinal member 12 is placed in a suitable holding fixture and the transverse members 10 are placed in the slots in the member 12. When this has been done, the top longitudinal member 11 is dropped into place and the ends of the members 11 and 12 are secured together in any desired manner, such as by the rivets 13 and 14. It will be seen that this method of assembly lends itself to economical large scale mass production of the grid element, and will effect substantial economies in the manufacture and assembly thereof.

Since all movement of the movable transverse members is controlled by the cam slots 15 and the followers 16, the first movement is in an angularly inclined movement in an upward direction. This is followed by a swinging movement of the transverse members 10. Thus it will be readily apparent that the force required to effect movement of the grid when frozen in an ice block is much less than would be necessary if it were necessary to first move the entire transverse grid member bodily against the ice cubes in a direction either longitudinally or horizontally of the pan to effect the initial movement and breaking of the ice cubes from the pan. The grid of the present invention provides for a direct application of a force to the pan which initiates the ice-freeing movement of the transverse members to separate the grid from the frozen ice block and to free the ice block from the pan by the application of force to the pan. The force is transferred to the transverse grid members by direct mechanical transfer

from the pan as well as from the ice mass. If desired, mechanical forces may be applied directly to the top edges of the transverse members 10 as disclosed in my co-pending application 46-9-1.

In constructing a grid of the present invention, I prefer to use a heat conducting material, such for example as sheet aluminum alloys, magnesium alloys, or the like, the surfaces of which have been treated to render them water repellent. One satisfactory method of accomplishing this when aluminum or the like is used, is to subject the parts to treatment in an anodizing bath and thereafter to seal the anodized surfaces. Another satisfactory method is to polish the surfaces and thereafter to treat the polished surfaces with a water-proofing material such, for example, as a finish containing a water impermeable plastic substance in which silicon has been substituted for carbon in the molecule and which are commercially known as "silicone" resins, which are now available commercially.

From the foregoing it will be understood that a grid construction embodying the present invention may be readily assembled from a plurality of parts, each of which may be separately fabricated. The parts are loosely held in their assembled relation so as to drop into position and occupy a predetermined position in the ice 30 pan.

I claim:

An ice tray grid comprising a longitudinal partition, a plurality of transverse members slidably mounted in said longitudinal partition and angularly disposed therein relative to each other to provide spaced ice blocks in the form of truncated wedges, certain of said blocks having their base portions adjacent the ice pan and other of said blocks having their truncated apices adjacent the ice pan whereby said first named blocks act as force applying members on said grid and said other of said blocks act as unlocking key members, and comprising a plurality of spaced arcuate cam slots in said longitudinal partition member and a rounded cam follower on the transverse partition member disposed in each of said slots.
